UNITED STATES PATENT OFFICE.

JOHN D. CURTIS, OF WORCESTER, MASSACHUSETTS, ASSIGNOR TO RICHARDSON MANUFACTURING COMPANY, OF WORCESTER, MASSACHUSETTS, A CORPORATION OF MASSACHUSETTS.

ROAD-SANDING MACHINE.

1,172,012.

Specification of Letters Patent. Patented Feb. 15, 1916.

Application filed August 26, 1912. Serial No. 717,018.

To all whom it may concern:

Be it known that I, JOHN D. CURTIS, a citizen of the United States, residing at Worcester, in the county of Worcester and 5 Commonwealth of Massachusetts, have invented a new and useful Improvement in Road-Sanding Machines, of which the following is a specification, accompanied by drawings forming a part of the same.

10 The object of my present invention is to provide an apparatus adapted to distribute sand uniformly over the surface of a highway and adapted to be used in connection with an apparatus for distributing oil or 15 similar material upon a highway. I accomplish this object by means of the construction and arrangement of parts as herein-after described, the novel features being pointed out in the annexed claims.

20 Referring to the accompanying drawings, Figure 1 represents a side elevation of an oiling and sanding apparatus, the latter being shown in sectional view and embodying my present invention. Fig. 2 is a top 25 view of the sanding apparatus.

Similar reference characters refer to similar parts in the different views.

Referring to the accompanying drawings, 1 denotes an oil tank or receptacle provided 30 with means for distributing oil, tarvia, bitumen, or the like, either in a heated or cold state upon the roadway through a series of pipes 2. The apparatus is supported upon wheels 3 having a pawl and ratchet connection with a rotating shaft passing beneath the tank 1 and provided on opposite sides of the tank with sprocket wheels, one of which is shown at 4, Fig. 1. The sills 5 and 6 of the tank 1 are extended rearwardly 35 and form a support for the sanding apparatus, the rear ends of the sills being supported upon a truck wheel 7.

The sanding apparatus comprises first, a receptacle for the sand, consisting in the 45 present instance of a hopper 8 having an opening at the bottom communicating with a sand pocket 9 into which sand flows by gravity from the hopper 8 through the opening 10; secondly, in a distributing mechanism 50 for applying the sand uniformly to the surface of the highway; and thirdly, in a transferring mechanism by which the sand is transferred at a predetermined rate from the sand receptacle to the sand distributing 55 mechanism. This latter element comprises

in the present instance an elevator belt 11 carried upon sprocket wheels having parallel shafts 12 and 13 and provided with cup shaped buckets 14. The elevator belt and buckets are moved in the direction of the arrow 15 by mechanism hereinafter described, by which the sand is carried from the pocket 9 and delivered upon an inclined surface 16 over which the sand gradually slides downward upon a narrow platform 17.

The distributing means by which the sand is laid uniformly upon the surface of the highway consists in the present instance of a reciprocating sieve 18 sliding in horizontal ways in the framework of the machine and given a short rapid reciprocating movement by means of a slotted cam 19. The surface of the sieve 18 is preferably slightly inclined, as represented in Fig. 1, to allow any accumulation too coarse to pass through the meshes of the sieve to fall over the edge 20 of the framework and be deposited upon the road.

In order to distribute the sand evenly over the surface of the reciprocating sieve I extend from the platform 17 a series of bars 21 transversely across the sieve and slightly raised above its upper surface. Motion is imparted to the movable parts of the apparatus from the sprocket wheels 4 to a shaft 22 mounted at the rear of the oil tank 1 upon the sills 5 and 6. The shaft 22 carries at one end a sprocket wheel 23 which imparts motion to the shaft 13 through a chain belt 24. The shaft 13 imparts a rotating movement through its sprocket wheels to the elevator belt 11. The shaft 13 through a chain belt 25 imparts rotation to a shaft 26 upon which is mounted the cam 19 having a cam slot 27 engaging a stud 28 projecting from the under side of the reciprocating sieve 18.

By placing the sanding apparatus at the rear of the oiling apparatus and locating the distributing mechanism in front of the truck 7, none of the supporting wheels are caused to pass over the unsanded and oiled portion of the roadway, the supporting wheels 3 traveling in advance of the oiled surface and the truck 7 at the rear of the sanded surface. The hopper 8 may be replenished by sand shoveled from a vehicle at its side and the amount of sand distributed over any given area may be readily controlled by

regulating the speed of the elevator belt 11 and also by regulating the reciprocating movement of the sieve 18.

I claim,

5. 1. In an apparatus of the class specified, a vehicle supported on wheels, means for distributing oil or the like over a roadway, and means behind said distributing means for spreading sand over the roadway, part 10 of the supporting wheels being in front of said distributing means and the remainder of the supporting wheels being behind the sand spreading means.
2. In apparatus of the class specified, a

wheeled vehicle providing an oil distributing means and a sand distributing means disposed consecutively thereon in the forward travel of the vehicle, and in advance of one or more of the supporting wheels thereof, whereby the travel of said wheel 20 or wheels over the oiled but unsanded roadway is avoided.

Dated this 22nd day of August, 1912.

JOHN D. CURTIS.
